UNITED STATES PATENT OFFICE.

EDWIN STRAIN, OF MELROSE, ASSIGNOR TO MILES S. CAHILL, OF BOSTON,
MASSACHUSETTS.

NEEDLE.

SPECIFICATION forming part of Letters Patent No. 353,040, dated November 23, 1886.

Application filed September 18, 1886. Serial No. 213,855. (No model.)

To all whom it may concern:

Be it known that I, EDWIN STRAIN, of Melrose, in the county of Middlesex and State of Massachusetts, a citizen of the United States, have invented a new and useful Improvement 5 in Needles, of which the following is a full, clear, and exact description, reference being had to the accompanying drawings, forming a part of this specification, in explaining its 10 nature.

The invention relates to a needle having a point and an eye, and adapted to hold a single thread or cord by its end, and to be readily secured thereto and detached therefrom. This 15 result is obtained by means of an eye of peculiar construction, made wider at one side of the needle-shank than at the other, and having a recess of peculiar shape extending from the eye to the end of the needle, which recess 20 is also wider at its base than at its opening, the eye and recess being so shaped that they are adapted to securely hold one end of a cord or thread in a manner to permit the cord or thread to extend from the end thereof, and not 25 project from the surface of the needle, at least to any appreciable extent.

In the drawings, Figure 1 is a view in elevation of a needle having the features of my invention and a thread or cord attached there- 30 to. Fig. 2 is a view in elevation to show the narrow part of the cross-slot and the entrance to the recess which extends therefrom. Fig. 3 is a view in elevation to show the wide opening to the cross-slot. Fig. 4 is an enlarged 35 view in vertical section, showing the relation of the cross-slot to the longitudinal recess opening or extending therefrom. Fig. 5 shows the same section with a section of cord or thread as it is when the needle is fastened or 40 secured thereto. Fig. 6 is a horizontal section upon the line $y-y$ of Fig. 4. Fig. 7 is a horizontal section upon the line $x-x$ of Fig. 4. Fig. 8 illustrates in section modifications hereinafter described.

45 a represents the needle. It has the point a' and the eye a'' . The eye is formed by means of a cross-slot, a^3 , having the wide entrance a^4 upon one side of the needle-shank and the narrow section a^5 upon the opposite side, the slot 50 being substantially V-shaped in cross-section.

From the narrow part of the slot there extends to the end or butt of the needle a longitudinal recess, a^6 . This is also V-shaped in cross section, or substantially V-shaped, the broad part of the recess being toward the center of the needle, while the opening a^7 is narrower. The point a^8 , where the recess and slot intersect, may be a right angle, but preferably is an acute angle, as represented in Figs. 8 and 9, so as to form a sharp or pointed surface or edge.

The recess a^6 may be deepened somewhat toward the butt, as represented in Fig. 8, and it may have the rounded outer corner, a^9 , as therein shown. The shank of the needle may 65 also be somewhat flattened or drawn in upon the surface a^{10} immediately about the wide entrance to the slot, if desired. (See Fig. 9.)

In use one end of the fastening thread or cord B is inserted from the wide side of the 70 cross-slot, passed through it until the length of the thread or cord which it is designed to use has been drawn through, when it is pulled forcibly against the sharp edge a^8 and through the narrow opening a^7 of the recess a^6 into the 75 recess, so that the thread or cord takes the position in the eye represented in Figs. 1 and 5. The cord or thread is then severed close to the slot of the needle, as represented in Fig. 5. The cord is by this means firmly and securely 80 attached to the needle, the end being inclosed and locked in the cross-slot a^3 and held nipped by confining the section of the cord or thread extending from it in the side recess, a^6 , of the needle, so that once nipped it is held so until 85 released. The needle, however, can be easily removed from the thread by another needle or sharp-pointed instrument, removing the end of the thread from the point or shoulder a^8 and drawing it outward through the narrow entrance to the cross-slot recess a^6 .

Such a needle as this is useful wherever it is desirable to sew with one thread or cord, and also where the needle is used for sewing closely-woven or close-textured goods—such, for instance, as leather—and it is particularly useful for sewing on or attaching buttons to the uppers of boots or shoes.

By extending the wide portion or entrance of the cross-slot downward, as represented in 90

Fig. 9, not only is the shoulder a made sharper, but a pocket or recess, a^{11} , is formed for receiving a portion of the end of the thread, and so that it shall not extend outward from the shank of the needle, and by flattening the shank about the entrance to said slot, or by drawing it in about the entrance to said slot, as above described, I am enabled to cut off the end of the thread, so that it shall not extend or project beyond the line of the greatest diameter of the needle, which is a very material advantage when the needle is used for drawing cord or thread through such a fabric as, for instance, leather, where there should be no projection of any kind extending beyond the surface of the needle.

By making the recess a^6 tapering inward near the butt I am enabled to bring the thread or cord very nearly central in relation to the center of the needle, providing holding-space for the thread or cord within the recess, and obtain a somewhat rounded surface for it to bear against, instead of a sharp corner, and at the same time improve the draft of the thread upon the holding edge or shoulder a^8 .

I prefer, in most instances, to make the sides of the slot a^3 to converge or come together immediately at the point a^8 , as shown in Figs. 2 and 3, as this provides a horizontal biting or nipping action upon the end of the cord, which is increased the greater the strain thereon. The longitudinal recess is made of any desired

depth, and is largely dependent upon the size of the thread or cord used. Where a large thread or cord is used, it will be desirable to extend the recess about two-thirds across the shank.

Having thus fully described my invention, I claim and desire to secure by Letters Patent of the United States—

1. A needle having a point, a' , and an eye formed by the cross-slot a^3 , wider on one side of the needle than on the other, and the recess a^6 , extending from the narrow section of said slot to the butt, substantially as described.

2. A needle having a point, a' , and an eye formed by the slot a^3 , V-shaped or substantially V-shaped in cross-section, the recess a^6 , opening therefrom, also V-shaped or substantially V-shaped in cross-section, and the shoulder a^8 , substantially as described.

3. In needles having the cross-slot a^3 and recess a^6 , the shoulder or edge a^8 , having the pocket a^{11} , extending downward below or beyond its pointed edge, as and for the purposes described.

4. In a needle having the cross-slot a^3 , the recess a^6 , made deeper at or near its outer end, as and for the purposes described.

EDWIN STRAIN.
